CLAIM

The ornamental design for a breathing tube with mesh, as shown and described.

DESCRIPTION

FIG. 1 is a top, front, and side perspective view of a breathing tube with mesh showing a tubing assembly embodying our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is an enlarged view of a portion of FIG. 4, showing a bead that is lined for the color blue being positioned between intervening portions of a wall of a conduit of the breathing tube with mesh.

Broken lines are used to illustrate portions of the breathing tube with mesh that form no part of the claimed design. The breathing tube with mesh is shown with a symbolic break in its length. The appearance of any portion of the article between the break lines forms no part of the claimed design.

The drawing is lined for color. The color and shading of the bead is a blue color value in the L*a*b* color space of L=42 to 48; a=10 to 18; b=-69 to -53 according to color measurement standard ISO 11664-4:2008(E)/CIE S 014-4/E: 2007.

(Continued)

The The mesh is composed of a translucent material and the tubing it surrounds can be seen through the mesh.
